M. D. Peck

UNITED STATES PATENT OFFICE.

ALVIN TAYLOR CHURCH, OF FARMINGTON, IOWA.

PEN-HOLDER.

SPECIFICATION forming part of Letters Patent No. 368,651, dated August 23, 1887.

Application filed April 25, 1887. Serial No. 236,110. (No model.)

To all whom it may concern:

Be it known that I, ALVIN TAYLOR CHURCH, a citizen of the United States, residing at Farmington, in the county of Van Buren and State 5 of Iowa, have invented certain new and useful Improvements in Pen-Holders; and I do hereby declare the following to be a full, clear, and exact description of the invention, such as will enable others skilled in the art to which it applies to make and use the same, reference being had to the accompanying drawings, which form part of this specification.

My invention relates to an improvement in pen-holders, and has for its object to so construct the holder of the pen that it shall serve as an external lever upon the handle to bind the pen thereon without weakening the handle, and at the same time provide means for such perfect release of the pen when the lever 20 is reversed that the soiled and worn-out pen can be thrown or shaken off without handling and soiling the fingers.

Heretofore in the construction of pen-holders provided with a lever for holding the pen 25 the holder has been so slit or bored for the insertion or attachment of the lever as to greatly weaken its parts, and provide recesses and cavities in which the backflowing ink accumulates and dries around the lever, rendering the 30 operation of releasing the pen very difficult without breaking the holder, on account of the dried ink in the recesses after a short period of time has elapsed.

The main object of my improvement is to 35 overcome these objections by a strong and much more simple device than has been used heretofore; and the invention consists in the construction hereinafter described, and more particularly pointed out in the claims.

Referring to the drawings, Figure 1 is a perspective view of my improved pen-holder. Fig. 2 is a longitudinal sectional view showing the pen secured in the holder. Fig. 3 is a longitudinal sectional view showing the pen released and the lever tilted away from the 45 holder. Fig. 4 is a perspective view of the detached lever.

Like letters of reference refer to corresponding parts in each figure of the drawings.

A represents the handle or holder, made of wood, rubber, ivory, bone, cork, or other suitable material, of any desired length, having its

lower portion, a, slightly reduced in diameter and beveled on its under side near its lower end, at C, to its lower extremity. On the upper part of the reduced portion a of the holder there is a ring, B, upset in its lower part to form an enlarged socket, b, on its inside to receive and hold the arm of the lever, said ring being adapted to slide up and down on the reduced portion of the holder.

D represents a lever having its body d made in the form of a ring, adapted to loosely encircle and fit the reduced portion a of the holder. From near the front and upper portion of the body of the lever there is a lever-arm, c, extending upward and backward, terminating in a dull point at some distance from the body. From the rear lower portion of the body d there is extended downward and forward a lip, e, of the same contour of the pen E and handle, for clasping the pen upon the handle. This lip is beveled on its lower end to conform substantially to the lower reduced portion of the holder.

The lever D is placed on the reduced portion a of the handle, so that the lower end of the lip e shall come even with the lower end of the beveled portion C of the holder, and then indentations f are made in the side of the upper portion of the body d with a suitable instrument, compressing the projections of the metal of the body made by the indentations into the sides of the material of the handle, thereby forming a pivot, upon which the lever 75 swings.

When it is desired to use a handle of metal, bone, ivory, vulcanite, gutta-percha, or of other material that cannot be indented with the metal of the lever, slight holes may be 80 made in its sides before placing the lever on the holder, and then the metal of the body of the lever depressed into the holes to form the pivotal bearing.

In operation, the socket-ring B is slid upward on the reduced portion a of the holder, releasing the lever-arm c, which drops down behind the holder, thereby raising the lip e to a distance above and in front of the lower end sufficient to enable the worn and soiled pen to 95 be thrown out without handling and to provide a free opening for the insertion of a new one. The lip e of the body is then brought down upon the pen as the lever-arm c is forced 100

up against the handle, holding the pen rigidly in position, while the ring B is slipped down, receiving and holding the upper end of the lever-arm within its socket.

5 Having fully described my invention, what I claim as new, and desire to secure by Letters Patent of the United States, is--

10 1. A pen-holder reduced in diameter in its lower portion, having a lever encircling the end of said reduced portion, pivotally connected thereto by projections formed by indentations in the lever which take into the sides of the body of the holder, said lever being adapted to clamp and hold a pen upon the 15 holder, as set forth.

15 2. The combination, with a pen-holder re-

duced in diameter in its lower portion, having a lever encircling the reduced portion and pivotally connected thereto by projections formed by indentations in the lever which 20 take into the sides of the holder, said lever having an arm on its under side extending backward, of a sliding ring on the reduced portion, upset, forming a socket at its lower end to receive the lever-arm, as set forth. 25

In testimony whereof I affix my signature in presence of two witnesses.

ALVIN TAYLOR CHURCH.
